UNITED STATES PATENT OFFICE.

HENRY L. NELSON, OF CANNON FALLS, MINNESOTA.

SHORT-TURN DEVICE FOR POLE TRUCKS.

Application filed August 31, 1923. Serial No. 660,364.

To all whom it may concern:

Be it known that I, HENRY L. NELSON, a citizen of the United States, residing at Cannon Falls, in the county of Goodhue and State of Minnesota, have invented certain new and useful Improvements in Short-Turn Devices for Pole Trucks, of which the following is a specification.

My invention relates to attachments for pole trucks of harvesting and other implements and the object is to provide a simple and efficient anti-tipping device for such trucks.

In the accompanying drawing:

Fig. 1 is a top view of a portion of a binder, the draw bar of said binder and pole truck for same with my improvement attached.

Fig. 2 is an enlarged section on line 2—2 in Fig. 1.

Fig. 3 is an elevation on line 3—3 in Fig. 2.

Referring to the drawing by reference numerals, 5 in Fig. 1 represents the front part of a binder or other farm implement to which is pivotally secured as at 6 a draw bar 7. 8 is a brace secured as at 9 to the draw bar and pivotally secured as at 10 on the implement, to brace the pole and keep it in right relation to the implement.

11 in Fig. 2 is a whiffletree pivoted on bar 7 as at 12 for drawing the binder by horse-power and it may also be a member of a suitable evener permitting more horses to be used on one side of the draft pole than the other. Said draft pole has its rear end pivotally supported on the axle 14, (as at 15) of a pole truck having two flanged wheels 16^R and 16^L journaled on the right and left ends respectively of said axle.

17 is a vertically disposed bracket secured as at 18 to the under side of bar 7 near its front end. The lower end of it is ball shaped as at 17^a to engage a socket 19 secured at 20 on the top side of the draft pole or tongue 13 at a point forward of the axle 14.

The construction above set forth is common to many pole trucks. My device involves a few minor changes in this construction and the securing of additional parts designed to prevent the tipping tendency of previous pole trucks whenever it is desired to make a turn. It will be readily under-

stood that in such former pole trucks the axle 14 and pole 13 are held rigidly at right angles to each other by angularly arranged braces 21 the rear ends of which are secured to the axle near each wheel and the front ends secured to the pole at a common point (not shown) forward of the axle 14. Thus when it is desired to make a left turn with the pole truck to about the position shown dotted in Fig. 1 the rigid position of the tongue 13 would be as indicated in dotted line 13^a and the direction of pull by the horses is indicated by arrow 13^{aa}. Said pull is of course exerted at pin 12 of the draw bar 7 and being directed in a direction to the left of its center, the draw bar through its ball joint exerts a direct side pressure on the truck pole 13. Inasmuch as the ball joint is forward of the axle the left turn causes the left truck wheel to swing under the draw bar 7 and the right hand wheel is swung forward obliquely. The pull at point 12 on the draw bar being to the left and the truck wheel 16^L being swung under said bar the side pressure has a tendency to make said left wheel dig into the ground and simultaneously wheel 16^R is forced upwardly and the result is a tipping of the entire pole truck that renders it practically useless.

I have found that by keeping the direction of the pull forward of pivot 12 as nearly as possible in a straight line with the longitudinal center of the draw bar, while a turn is being made, the pole truck may be turned at a comparatively sharp angle and no tipping will occur. The means for accomplishing this are as follows:

The draft pole or tongue 13 is pivotally secured to the axle 14 (as at 15 in Figs. 2 and 3) and the axle braces 21 have their front ends secured together by a vertical bolt 22 which is passed through the center of a bar 23 arranged longitudinally under the tongue and the draw bar. The forward end of said bar is pivotally secured as at 24 to the under side of the draft pole 13 and the rear end of the bar is loosely bolted and supported as at 25 (Figs. 2 and 3) on the horizontal part of a U-shaped hanger suspended from a horizontally arranged bolt 27 in draw bar 7. Bolts 24 and 25 are equidistant from bolt 22 and the bar 23 is preferably a heavy flat steel bar. In making a

turn, for example to the left, let it be assumed that the horses draw the pole 13 to position 13^b (Fig. 1). The bar 23 is of course drawn out of alinement with the center lines of the draw bar 7 and tongue 13 and in so moving the bolt 22 at its center is drawn to the left as to 22^x to one side of the original alinement. The pivot bolt 22^a being secured to the braces 21 thus cause the axle 14 and wheels 16 to be turned faster than the tongue, the result being that as long as turning of the pole or tongue 13^b is taking place there is a side strain of bar 23 which being fixed with relation to the axle, the pole 13 gradually assumes a more obtuse angle with relation to the axle. This side movement of tongue or pole 13 and consequent swinging of the axle creates what may be called a side strain or tension 20 in the parts just described, all in a horizontal plane underneath the draft pole or tongue 13 and level with the axle. The turning force thus being exerted on a low level and the level of the axle there is no other force tending to tip the truck axle, the wheels of which will ride on the ground 25 in their proper horizontal relation.

What I claim is:—

In a pole truck device of the class described, a two wheeled truck, a tongue pivotally secured on the axle of said truck and normally at right angles thereto, means adjacent said pivot on the tongue for pivotally supporting a draw bar of an agricultural implement, means mounted to operate substantially in a horizontal plane with the truck axle and operatively connected with said axle, the tongue and the draw bar, to swing the pole truck more rapidly than the tongue when the tongue and the draw bar are brought out of alinement with each other, said means comprising a bar arranged longitudinally under the draw bar and draft pole, the forward end of said bar pivotally secured to the tongue forward of the truck 45 axle and the rear end of said bar pivotally secured to a hanger bracket depending from the draft pole rearward of the truck axle, axle braces secured to the axle at points adjacent the wheels and extending forwardly 50 diagonally to a common pivot on said bar.

In testimony whereof I affix my signature.

HENRY L. NELSON.
